His Attorney.

UNITED STATES PATENT OFFICE.

CHARLES V. FERGUSON, OF SCHENECTADY, NEW YORK, ASSIGNOR TO GENERAL ELECTRIC COMPANY, A CORPORATION OF NEW YORK.

INCLOSED-ARC DEVICE.

1,267,858.

Specification of Letters Patent. Patented May 28, 1918.

Application filed July 3, 1916. Serial No. 107,276.

To all whom it may concern:

Be it known that I, CHARLES V. FERGUSON, a citizen of the United States, residing at Schenectady, in the county of Schenectady, State of New York, have invented certain new and useful Improvements in Inclosed-Arc Devices, of which the following is a specification.

The present invention relates to devices in which an arc is operated between an incandescent cathode and an anode operating below the temperature of appreciable electron emission, in a sealed envelop, such, for example, as the incandescent cathode rectifier described in Meikle Patent No. 1,182,290. In the rectifier described in this patent an arc is operated between a heated tungsten cathode and an anode of tungsten, or other suitable conductive material, in an atmosphere of inert gas, such, for example, as nitrogen, argon, or mercury vapor. It is stated in the patent that electronegative gases such as water vapor, oxygen and chlorin must be carefully excluded to avoid deleterious disintegration of the cathode.

I have discovered that iodin vapor constitutes a striking exception among electronegative gases in an incandescent cathode device. Not only is the electrical disintegration of the cathode in an arc device containing iodin negligible, but iodin on the other hand possesses distinctive properties advantageous to the operation of an arc particularly in a rectifier. One of the main advantages of iodin vapor in a rectifier is the substantial inhibition of arcing from an electrode not intended to act as cathode, for example, from anode to cathode, or between two anodes. The voltage drop of an arc in iodin vapor is relatively low and substantially invariable.

The accompanying drawing shows one specific form of hot cathode device embodying my invention. I wish it to be understood that this is shown for illustrative purposes only as my invention is of general application. The particular cathode structure shown is described and claimed in another copending application.

Referring to the drawing, the device shown comprises a cathode 1, consisting of tungsten, or other suitable refractory mate-

rial, and an anode 2, which also consists of tungsten, molybdenum, copper or other suitable conductive material. An anode conductor 3, and cathode conductors 4, 5, are sealed into the envelop 6 in the usual manner. The structural features of the electrodes are not part of the present invention.

When the envelop has been evacuated in the usual manner, water vapor being carefully removed, some pure iodin is introduced, for example, through a side tube afterward sealed off and not shown in the drawing. The quantity of iodin should be sufficient and the operating temperature of the bulb high enough to create a pressure of iodin vapor equal to at least about one-half millimeter of mercury. The best rectification appears to be obtained at pressures up to about 50 millimeters.

The drop of voltage in an arc of about five amperes in iodin vapor is about 23 volts. The tendency for arcing to occur from anode to cathode upon the reversal of polarity is so low that alternating currents of high voltage, for example, 700 to 800 volts, may be readily rectified in iodin vapor.

What I claim as new and desire to secure by Letters Patent of the United States, is:

1. The combination of a container, a cathode which is refractory enough to be operable at incandescence, an anode and a quantity of iodin within said container.

2. A rectifier comprising the combination of a tungsten cathode proportioned to operate at incandescence, a co-operating anode and a quantity of iodin, an inclosing container, said container operating at a temperature at which the iodin has a vapor pressure exceeding about one-half millimeter of mercury.

3. The method of suppressing deleterious arcing from anode to cathode in an arc device provided with a cathode operating at incandescence and an anode operating below the temperature at which electron emission is appreciable, which consists in providing an environment of iodin vapor for the arc during the operation of the device.

In witness whereof, I have hereunto set my hand this 30th day of June, 1916.

CHARLES V. FERGUSON.
